SHAFT MUCKER

Joseph V. Grismer, Silverton, Idaho

Application December 9, 1946, Serial No. 715,069

3. Claims. (CL 214—141)

1

This invention relates to a shaft mucker and it is one object of the invention to provide a device of this character wherein a frame is built in a shaft and has associated with it a mucking apparatus by means of which dirt and rock is removed from the bottom of the shaft and deposited in a bucket by means of which it is to be hoisted from the shaft.

Another object of the invention is to provide a mucker of this type wherein a scoop bucket for removing dirt and rock from the bottom of a shaft is carried by a hook so mounted that it may be shifted longitudinally and also swung vertically and horizontally so that the scoop bucket may be moved into position for removing rock and dirt from all portions of the bottom of the shaft and the dirt and rock then dumped into a hoisting bucket.

Another object of the invention is to provide a shaft mucker having improved means for controlling movements of the boom carrying the scoop bucket, this controlling means being so constructed and arranged that it may be operated by one workman standing near the bottom of the frame erected in the shaft.

Another object of the invention is to provide a shaft mucker having a support for the boom which is firmly mounted across the bottom of the frame but can be easily and quickly shifted to a lower position when additional framing is added as the shaft is deepened.

Another object of the invention is to provide a shaft mucker which is comparatively simple in construction and easy to operate.

The invention is illustrated in the accompanying drawings wherein:

Fig. 1 is a view showing the frame in vertical section and the mucking apparatus in side elevation.

Fig. 2 is a similar view showing the mucking apparatus in front elevation.

Fig. 3 is a view showing the frame in transverse section and the mucking apparatus in top plan.

Fig. 4 is a fragmentary sectional view taken along the line 4—4 of Figure 3.

Fig. 5 is a sectional view taken along the line 5—5 of Figure 3.

The shaft 1 is dug vertically in the ground and as it is deepened a frame is erected in the shaft. This frame is formed of heavy beams and has a suitable number of vertically extending beams 2 and horizontally extending beams or cross-stringers 3 and 4. Since certain of the cross beams 4 may be in the way of the mucking

2

mechanism these particular cross beams may be temporarily omitted at the bottom of the frame until the shaft has been dug to such a depth that additional framing has been added to the lower end of the frame and the mucking apparatus lowered to a new position at the bottom of the frame.

Dirt and rock are to be dug from the bottom of the shaft by means of a scoop bucket or shovel 5 which is mounted between the forks or arms 6 at the front end of a boom 11. The boom is square in cross section and may be formed of two channel beams having the edges of their side flanges welded to each other, as shown in Figure 4, or as a unit if so desired. This boom slidably passes through a tubular sleeve or casing 8 which extends through a rectangular frame 9 having outstanding flanges 10 along its edges and at its top and bottom the frame is formed midway its width with openings 11 to receive trunnions 12 carried by plates 13 which are secured to the frame by bolts 14. The trunnions engage through bushings 15 mounted through upper and lower portions of the casing 8 and mounting the casing and the boom for swinging movement transversely of the shaft and thus allowing the scoop to be shifted transversely of the shaft into position for clearing dirt and rock from the bottom of the shaft for the full width thereof.

Pipes or tubular rocker shafts 16 and 17 extend from opposite sides of the frame 9 and are rotatably mounted through bearings 18 and 19. The bearing 18 is provided with a shoe 20 for fitting about the side beam 3 toward which the shaft 17 extends and the bearing 18 carries a plate 21 through which set screws 22 are threaded and journaled to a shoe 23 so that this shoe may be shifted toward and away from the shaft 16 and thus moved into and out of gripping engagement with a beam 3 at the opposite side of the shaft from the beam engaged by the shoe 20. It will thus be seen that the bearings may be mounted at opposite sides of the lower end of the frame 9 erected in the shaft and since the frame 9 turns with the rocker shafts the boom may have vertical swinging movement and thus impart scooping movement to the bucket or shovel 5 during removal of dirt and rock from the bottom of the shaft, and filling of the bucket 24 by means of which the dirt and rock are hoisted from the shaft.

Sliding movement of the boom through the casing 8 is controlled by a brake 25 mounted in 55 an internal recess at one side of the casing 8

and has a shank 26 which projects outwardly from the casing through an opening 27 and is pivoted to a rod 28 which passes through a slot 29 formed in the confronting side wall of the frame 9 and extends longitudinally in the rocker shaft 16. The rod is pivotally connected with a piston 30 which is slidable longitudinally in the rocker shaft and since the end portion of the rocker shaft in which the piston operates is blocked by a partition 31 this portion of the rocker shaft forms a cylinder for the piston. A flexible tube or hose 32 leads from a valve 33 to the portion of the rocker shaft or cylinder between the piston and the partition 31 and this valve is connected with a suitable source of air under pressure. By actuating the valve air may be admitted into the cylinder to shift the piston longitudinally and force the brake into gripping engagement with the boom and upon again actuating the valve the air may be allowed to escape and thus allow the brake to move to a position for releasing the boom and allowing the boom to slide through the casing. It will thus be seen that during use of the mucker the boom may be allowed to slide through the casing as the bucket 5 is moved toward the position indicated by dotted lines in Figure 1 and so held as the boom is swung forwardly for scooping rock and dirt from the bottom of the shaft. During this forward movement the brake may be released so that the boom may slide rearwardly until the bucket 5 is over the bucket 24 and the brake then again applied to hold the boom stationary and maintain the bucket 5 in position over the bucket 24 while the hinged bottom 33 of the bucket 5 is released by the trip rope 34 and allowed to swing to the dumping position. The scoop bucket is pivotally mounted between the forms or arms by pivot pins 35 and held in an angularly adjusted position by pins 36 which are passed through openings in the forks and through selected ones of the openings 37 formed through side walls of the bucket.

Transverse swinging movement of the sleeve or casing 8 about the trunnions 12 for shifting the boom transversely of the shaft and allowing dirt and rock to be scooped from all portions of the bottom of the shaft is accomplished by means of a cylinder 38 which has one end connected with the rocker shaft 17 by a bar 39 and in which operates a piston 40 having its piston rod 41 projecting from the inner or front end of the cylinder and connected with an ear 42 projecting laterally from the front end portion of the sleeve or casing 8. Flexible tubes or hoses 43 lead from end portions of the cylinder 38 to the valve 33 so that by manipulating this valve flow of air through the tubes may be controlled and the piston slid in the cylinder to shift the casing and the boom transversely of the shaft to adjusted positions. The valve 33 is a conventional master valve and it will be understood that if desired separate valves may be provided for controlling flow of air through the tubes 32 and 43.

In order to control movements of the boom and scooping or digging of rock and dirt from the bottom of the shaft there have been provided cables 44 and 45. These cables are wound about hoisting drums 46 and 47. The cable 44 extends downwardly from the drum 46 and across a roller 48, and after is then trained about the pulley 49 carried by the scoop bucket 5 and secured at its lower end to a screw eye carried by a cross beam 4 at the lower end of the frame. The cable 45 extends downwardly from the drum 47 and after being trained about a pulley 51 is attached to an

ear 52 at the rear edge of the bottom of the scoop bucket. Rotation of the drums is controlled by controls 53 and 54 having adjusting handles 55 and 56 from ends of which extend pull ropes 57, 58, 59 and 60. These ropes are passed through eyes 61 so that their lower ends will be held in position to be grasped by a workman standing at the lower end of the frame near the valve 33. By actuating the control 53 to allow the cable 44 to unwind from the drum 46 and actuating the control 54 to cause the cable 45 to be wound upon the drum 47 the boom may be swung to the position indicated by dotted lines in Figure 1 and the cable 44 may then be wound upon the drum 46 to draw the scoop bucket forwardly and upwardly with a load of rock and dirt to a position over the bucket 24 where it will be held by applying the brake 25 and the trip line 34 then pulled to release the bottom 33 of the scoop bucket and allow this bottom to swing to an opened position for dumping contents of the scoop bucket into the hoisting bucket. After the hoisting bucket 24 has been filled it is raised from the shaft and emptied and again lowered for refilling. When the depth 25 of the shaft becomes such that rock and dirt can not be removed by the scoop bucket additional framing is added at the lower end of the frame erected in the shaft and the mucker mechanism lowered to the added framing.

30 Having thus described the invention what is claimed is:

1. A shaft mucker comprising a frame erected in a shaft, the shaft-frame being formed of beams secured to each other whereby the depth 35 of the frame may be increased as the shaft is deepened, a scoop at the lower end of the frame having a bucket and a boom carrying the bucket and extending rearwardly therefrom, an open frame extending transversely of the shaft frame and mounted for rocking movement about a horizontal axis extending transversely of the shaft frame, a sleeve extending through the open frame and through which the boom slidably passes, said sleeve being pivoted in the open frame for swinging movement transversely of the shaft about a vertical axis, a brake movable through a wall of the sleeve into and out of position for gripping the boom and releasably holding the boom against sliding movement longitudinally through 50 the sleeve, a cylinder forming a portion of the horizontal axis of the open frame, a piston slideable longitudinally in said cylinder and having a piston rod extending from the inner end of the cylinder into the open frame and connected with 55 said brake for applying and releasing the brake during movements of the piston, a second cylinder, a piston slideable longitudinally in the second cylinder and having a piston rod extending outwardly through one end of the cylinder and connected with said sleeve for swinging the sleeve and the boom transversely in the shaft about the vertical axis of the sleeve, and cable connected with the bucket for controlling vertical tilting of the boom and the open frame about the horizontal axis of the open frame and imparting dipping movements to the bucket for scooping material from the bottom of the shaft.

2. A shaft mucker comprising a frame erected in a shaft, the shaft-frame being formed of horizontally and vertically extending beams, a scoop at the lower end of the frame having a bucket and a boom carrying the bucket and extending rearwardly therefrom, an open frame extending transversely of the shaft frame, rocker shafts 75 extending from opposite sides of said open frame,

a shoe at the outer end of one rocker shaft for engaging a horizontally extending beam of the shaft-frame, said shoe constituting a bearing rotatably supporting the companion rocker shaft, a bearing for the other rocker shaft, a shoe for engaging second horizontal beam of the shaft-frame, screws threaded through the last mentioned shoe for firmly holding the said shoes in gripping engagement with the companion horizontally extending beams and removably supporting rocker shaft and the open frame in the shaft-frame, a sleeve extending horizontally through the open frame and through which the boom slidably passes, said sleeve being pivoted in the open frame for swinging movement transversely of the shaft about a vertical axis, means for swinging the sleeve and the boom transversely of the open frame about the vertical axis, and means for controlling vertical tilting of the sleeve and the open frame about the horizontal axis of the open frame and imparting dipping movements to the bucket for scooping material from the bottom of the shaft being dug.

3. A shaft mucker comprising a frame erected in a shaft, the shaft-frame being formed of beams secured to each other whereby the depth of the frame may be increased as the shaft is deepened, a scoop at the lower end of the frame having a bucket and a boom carrying the bucket and extending rearwardly therefrom, an open frame extending transversely in the shaft frame and mounted for rocking movement about a horizontal axis extending transversely of the shaft frame, a sleeve extending horizontally through the open frame and through which the boom slidably passes, said sleeve being pivoted in the open

5
10
15

frame for swinging movement transversely of the shaft about a vertical axis, means for swinging the sleeve and the boom transversely of the open frame about the vertical axis, drums mounted in the shaft frame, cables wound about said drums and having portions extending downwardly in the shaft and connected with front and rear portions of the bucket, said drums being controlled by valves having cross heads constituting handles for the valves, and operating lines for the valves extending from ends of their handles downwardly in the shaft frame to a position in which they may be grasped by an operator in the shaft frame and pull exerted upon the lines to open and close the valves.
